FEEDING SPOON

Carolyn S. Geckler, 1409 SW. 67, Oklahoma City, Okla.
Filed June 23, 1960, Ser. No. 38,178
2 Claims. (Cl. 30—324)

The present invention relates to spoons, and the like, and more particularly to a spoon for feeding infants.

Conventionally shaped spoons are unsatisfactory for training infants to eat semi-solid foods for the reason that an infant during the first few weeks has not learned to compress its lips to accept and hold food within its mouth. A conventional spoon must be tipped upwardly at the handle end to scrape the food out of the spoon against the infant's upper gum. This action causes the sides of the spoon to contact the infant's gums and, being hard and an unfamiliar sensation to the infant's mouth, the infant tries to reject the spoon by pushing it out of its mouth by pushing its tongue against the spoon and food. A conventional spoon is not shaped properly for efficiently scraping rejected food off an infant's lips and chin to return the food to the mouth. Furthermore, the conventional spoon, formed of metal, hurts the gums of an infant when it bites on the spoon, this is particularly true when the infant is teething.

It is, therefore, the principal object of the instant invention to provide a resilient type spoon for feeding infants.

Another object is to provide a substantially flat feeding spoon in which the spoon portion is removably carried by a handle portion.

Another object is to provide a spoon of this class formed of resilient material, such as rubber, having sufficient rigidity to retain its shape and yet not present a hard surface which might injure an infant's gum.

Another object is to provide a spoon-like tip which may be easily and quickly removed from the connecting handle portion and replaced with a clean tip.

A further object is to provide a feeding spoon having a removable tip which may be removed and sterilized as by boiling.

Still another object is to provide an infant's feeding spoon wherein the tip may be quickly and easily replaced with a sterilized tip when the spoon has been dropped or becomes dirty.

A further object is to provide a replaceable spoon-like tip for a handle wherein the spoon tip is provided with a rounded forward edge surface perpendicular to the longitudinal axis of the tip and handle.

The present invention accomplishes these and other objects by providing a substantially spade-shaped spoon-like tip end portion having an opposite cylindrical end portion removably received by a socket formed in one end of a handle member.

Other objects will be apparent from the following description when taken in conjunction with the accompanying single sheet of drawings, wherein:

FIGURE 1 is a top plan view, partly in section, of the handle and spoon tip in exploded relation; and,

FIGURES 2, 3 and 4, are vertical cross-sectional views taken substantially along the lines 2—2, 3—3 and 4—4, respectively, of FIG. 1.

Like characters of reference designate like parts in those figures of the drawings in which they occur.

In the drawings:

The reference numeral 10 indicates the device, as a whole, comprising an elongated handle member 12 having a socket 14 formed in one cylindrical-like end. The handle 12 may be formed of metal or any suitable preferably rigid material. The walls defining the socket 14 may be threaded, as at 16, or formed with inwardly

2

projecting ridges for the purposes which will presently be apparent.

The numeral 20 indicates a food dipping spade-like spoon tip end portion preferably formed of resilient material such as the rubber presently used in forming bottle nursing nipples. The spoon tip 20 has one cylindrical-like end 22 adapted to be closely received by the handle socket 14. A relatively small air release hole 15 extends laterally through the wall of the handle adjacent the inner end of the socket 14. Adjacent the cylindrical end 22, the body of the spoon is transversely widened a selected width, preferably relatively small. The opposing side edges 24 and 26 converge toward the forward end edge 28 of the spoon tip which latter is perpendicular to the longitudinal axis of the spoon tip and handle. The body of the tip, adjacent the cylindrical portion 22, is of substantially equal thickness, as at 30, to provide rigidity for the spoon tip. The greater forward portion of the tip is recessed in its upper surface, as at 32, to provide a substantially flat surface 34 parallel with the spoon tip bottom surface 36. The upper surface of the side edge portions 38, defining the recess 32, converge forwardly and blend with the flat surface 34. The spacing between the parallel upper and lower surfaces 34 and 36 is relatively small to provide a relatively thin forward end portion of the spoon. The side edges 24 and 26 and the end 28 are joined by a rounded edge surface formed on a relatively small radius as at 40. The upper and lower parallel surfaces 34 and 36 are similarly joined by a relatively small radius, as at 42, to provide an edge surface pleasing to the touch.

Operation

The spoon tip cylindrical end portion 22 is manually forced into the handle socket 14 or it may be rotated thereinto by a screw type action. Thereafter the device 10 is held by its handle portion 12 while the spoon-like tip end portion 20 is dipped into the infant's food, not shown, to place the food on the flat portion 34 which is then introduced into the infant's mouth. By tipping the handle portion of the spoon upwardly, the food, not shown, may be easily scraped off of the tip portion against the infant's upper gum. Any food rejected or spit out by the infant may be easily recollected off the infant's lips or chin by scraping the rounded free end edge 28 of the spoon over the infant's face. The spoon tip portion 20, after use, may be removed from the handle and sterilized, as by boiling, in a manner commonly followed in sterilizing bottle nipples and other instruments.

Obviously the invention is susceptible to some change or alteration without defeating its practicability, and I therefore do not wish to be confined to the preferred embodiment shown in the drawings and described herein, further than I am limited by the scope of the appended claims.

I claim:

1. An infant feeding spoon, comprising: an elongated handle portion formed of rigid material having one cylindrical end portion, said cylindrical end portion having a cylindrical socket formed therein coaxial with the longitudinal axis of the handle and having a plurality of thread-like projections formed on the wall defining the socket throughout the length thereof; and a food dipping member formed of resilient material, said member having a relatively thin forward portion terminating in a forward end edge perpendicular to its longitudinal axis and having upper and lower substantially parallel surfaces extending rearwardly of the forward end edge, the end portion of said member opposite its forward end edge having a cylindrical portion removably received by the socket in said handle, the diameter of said cylindrical portion being substantially greater than the spacing be-

tween said upper and lower parallel surfaces, said member having opposing side edges extending rearwardly from said forward end edge in diverging relation to form an intermediate transversely widened and thickened portion characterized by arcuate surfaces merging with said cylindrical portion.

2. An infant feeding spoon, comprising: an elongated handle portion formed of rigid material having one cylindrical end portion, said cylindrical end portion having a cylindrical socket formed therein coaxial with the longitudinal axis of the handle and having a plurality of thread-like projections formed on the wall defining the socket throughout the length thereof; and a food dipping member formed of resilient material, said member having a relatively thin forward portion defined by upper and lower substantially parallel surfaces merging at the forward end of the relatively thin portion in an arcuate end edge perpendicular to the longitudinal axis of said member, the end of said member, opposite the forward end edge, having a cylindrical portion removably received by the socket in said handle, the diameter of said cylindrical portion being substantially greater than the spacing between said upper and lower parallel surfaces, said member having opposing side edge portions extending

rearwardly in diverging relation from said forward end edge and inclined upwardly from said upper surface to form an intermediate transversely widened and thickened portion substantially equal in thickness to the diameter of said cylindrical portion and characterized by arcuate surfaces merging with said cylindrical portion and the upper surface of said relatively thin forward portion and defining a recess intermediate the width of said transversely widened and thickened portion.
